**Morris I. Lester, Allen Braver, and Garson Lester,
Detroit, Mich.**

Application May 27, 1946, Serial No. 130,112

Term of patent 7 years

(Cl. D44—10)

To all whom it may concern:

Be it known that we, Morris I. Lester, Allen Braver, and Garson Lester, citizens of the United States of America, residing at Detroit, in the county of Wayne and State of Michigan, have invented a new, original, and ornamental Design for a Tray, of which the following is a specification, reference being had therein to the accompanying drawing, forming a part thereof, wherein:

Figure 1 is a perspective view of a tray showing our new design;

Figure 2 is a side elevation thereof;

Figure 3 is a section on the line 3—3 of Figure 1; and

Figure 4 is a section on the line 4—4 of Figure 1.

We claim:

The ornamental design for a tray, substantially as shown.

MORRIS I. LESTER.
ALLEN BRAVER.
GARSON LESTER.
